Harry Rosenthal

UNITED STATES PATENT OFFICE.

LOUIS GRAVEURE, OF NEW YORK, N. Y.

GOLF CLUB.

Application filed September 21, 1927. Serial No. 220,886.

This invention relates to a golf club and has for its object to provide an article of this character which shall be so shaped as to render it particularly efficient for use in playing the game, especially for short strokes or putts. My improved golf club is so designed that it may be used efficiently by either right-handed or left-handed persons and it is so arranged that its striking faces are located in such a position as to avoid "topping" of the ball or otherwise making poor strokes. The rules of the game of golf prohibit the use of a golf club of the mallet type, although a club of such type is particularly effective for certain kinds of strokes. In my improved golf club, I have endeavored to maintain the mallet principle, at the same time producing a club which shall be so shaped as to present a form which shall not be inadmissible under golfing rules.

These and many other objects are attained by my invention, a more particular description of which will appear hereinafter and be more definitely pointed out in the claims appended hereto.

Reference is to be had to the accompanying drawing forming a part hereof in which—

Figure 1 is a side elevation of the head of my improved golf club;

Figure 2 is a front elevation of the same; and

Figure 3 is a sectional view on the line 3—3 of Figure 1, looking in the direction of the arrows.

Throughout the various views of the drawings, similar reference characters designate similar parts.

In the embodiment of my invention disclosed in the accompanying drawing, 1 indicates the golf club head which is provided with a blade 2. Said blade 2 is substantially wedge-shaped in cross-section with its widest edge 3 located at the bottom of the club and its narrower edge 4 at the top. Said blade is therefore provided with the inclined faces 5 as is clearly shown in Figure 2.

At 6 is shown a pair of cylindrical projections which extend laterally from the inclined faces 5 of the blade 2. Said projections are preferably located at the center line of the blade 2 and their outer ends or faces 7, which are absolutely vertical may be suitably roughened or serrated as at 8 to provide a desirable striking surface for the ball.

It is desirable to make said projections 6

of a diameter slightly greater than the diameter of a golf ball, and to provide the proper balance for the club, the projections may be hollow and thus contain a chamber 9 into which a suitable weighting substance 60 such as lead may be placed. In order to permit entrance to the chamber 9, openings 10 are provided through the striking faces 8, through which the lead may be poured.

At 11 is shown the haft-receiving boss 65 which extends upwardly from the upper edge 4 of the blade, said boss 11 being slightly inclined as shown and so located that the center of the head's weight is at the tip of the central axis of the boss 11. Said 70 boss is adapted to receive the usual haft 12 and it is reinforced at its lower end by longitudinally-extending webs 13 which curve downwardly from the boss and connect to the upper edge 4 of the blade 2. 75

At 14 is shown a pair of similar reinforcing webs which extend from the sides of the boss 11 and connect to the upper face of the cylindrical projections 1. Through the arrangement of reinforcing webs 13 and 14, 80 the boss is very firmly connected to the head so that the possibility of breakage is avoided. The arrangement of webs permits the same to be used as a guide for holding the club in putting and enables the user of the 85 club to properly sight and align the ball with the striking faces 7 so that the possibility of a poor shot being made is avoided.

The club is preferably made of aluminum, duralumin, or aluminum alloys so that a very 90 light club is provided which can be weighted to suit individual uses. The shape of the club is such as to provide the desirable mallet effect and create the tendency to cause the user to combine the three main 95 excellent ways of putting, that is, utilizing the pendulum, striking, and pushing actions. The shape of the club also, and its means of reinforcement render it capable of individual uses which will be readily apparent to the ardent golf enthusiast. 100

A distinct feature of the device is the extended or projected striking faces which are as heretofore described projected out beyond the plane of the blade and these 105 faces being truly vertical cause the ball to be struck solidly and uniformly, avoiding the possibility of erratic shots.

Having described one embodiment of my invention, it is obvious that the same is not 110

2
to be restricted thereto, but is broad enough to cover all structures coming within the scope of the annexed claims.

Having described my invention, what I claim is:

1. A golf club having a head composed of a blade member, projections extending from the opposite faces of said blade member, and striking surfaces on the ends of said projections.
2. A golf club having a head composed of a blade member and a pair of cylindrical projections extending from said blade.
3. A golf club having a head composed of a blade member and a protuberance extending from one of the faces of said blade, said protuberance having a flat outer end comprising a ball-striking surface.
4. A golf club head having a blade, said blade having a pair of side faces, a cylindrical projection extending outwardly from each of said side faces, each of said projections being provided with a flat outer termination forming a ball-striking face.
5. A golf club head having a blade, a pair of outwardly extending projections on said blade, each of said projections having a ball-striking surface at their outer terminations, a haft-receiving boss, webs ex-

tending longitudinally of the blade and connecting the boss with said blade, and webs extending transversely of the blade and connecting the boss with said projections.

6. A golf club having a haft-receiving boss, a head connected thereto, webs extending longitudinally of the head and connecting the same with the boss, and other webs extending at right angles to the first mentioned webs for connecting the head with the boss, said various webs co-operating to form an arrangement for sighting the ball when the club is being used.

7. A golf club head comprising a pair of cylindrical parts, a haft-receiving boss extending upwardly therefrom, and a blade member extending forwardly from between said cylindrical parts, and also extending to the rear of said boss.

8. A golf club head having a wedge-shaped blade, a cylindrical projection extending from a point located substantially at the center of each of the side faces of said blade, and a striking face on the end of each of said projections.

Signed at the city of New York, county of New York and State of New York, this 20th day of September, 1927.

LOUIS GRAVEURE.
